UNITED STATES PATENT OFFICE.

CHARLES S. RIDER, OF CANTON, OHIO.

MACHINE FOR REDUCING GRAIN TO FLOUR AND MIDDLEDINGS.

SPECIFICATION forming part of Letters Patent No. 268,729, dated December 5, 1882.

Application filed August 10, 1882. (No model.)

To all whom it may concern:

Be it known that I, CHARLES S. RIDER, a citizen of the United States, residing at Canton, in the county of Stark and State of Ohio, have invented certain new and useful Improvements in Machines for Reducing Grain to Flour and Middledings, of which the following is a specification, reference being had therein to the accompanying drawings.

Figure 1 is a side elevation of a grinding-machine embodying my improvements. Fig. 2 is an end view. Fig. 3 is a top plan view of the grinding devices. Fig. 4 is a horizontal section of the sliding plate or bar and a stationary one. Fig. 5 is a view of the operative face of the stationary plate. Fig. 6 is a similar view of the reciprocating plate or bar.

In the drawings I have shown the operative parts of the machine as being mounted on a frame-work, consisting of the legs or standards A A, girts B B, and top pieces, C C. The frame-work, however, can be varied to any desired extent without materially affecting the essential parts of the invention, as will be readily understood. Upon the frame-work described I mount a set of devices for breaking, cracking, or grinding the grain, consisting of a horizontal stationary surface and a reciprocating surface. The former surface is formed upon an elongated plate or bar, E, which is preferably attached to the frame-work in such manner as to be adjustable thereon. The attaching devices shown consist of slotted ears or arms projecting laterally from the plate or bar E, and set-screws e³, passing through slots theron. This plate rests upon one of the top pieces, C, of the frame, its operative face being in a vertical plane between the two said cross-pieces C C. The set-screws e³ e³ engage with the upper side of the cross-piece C upon which the grinding-plate E rests. Opposite to this plate or bar there is a reciprocating plate, G, mounted parallel to the former, and adapted to break, crack, or grind the grain or meal between its operative face and the face D' of the part E. The said operative face of the part G is corrugated, recessed, or ribbed in the manner shown at G', so that it may properly engage with the berries of the grain or with the particles of meal and effect the breaking or cracking.

The reciprocating mechanism which I have shown consists of a power-shaft, H, an eccentric, H', fastened thereto, and a vibrating forked lever, I. The lever I, by means of the forked arms i, engages with the eccentric, and by means of a smaller fork, at i', engages with an arm; g, projecting laterally from the reciprocating plate G. The lever is pivoted at i² to the top cross-piece, C, though it may be secured in any other suitable stationary part. Power is imparted to the shaft H by means of a belt-wheel, H², or in any other suitable manner, and it will be seen that when the shaft is rotating a reciprocating movement in horizontal paths will be imparted to the grinding-plate G. This plate or bar G is held in proper position vertically by means of the supporting cross-piece, or by springs, and is held properly relatively to the stationary grinding-plate by means of a guide or way provided by a supporting-piece, G², behind or outside of the plate or bar G, and fastened to the top of the cross-piece C. The operative faces of the stationary grinding or cracking plate or bar E and of the reciprocating plate or bar G are at their upper edges beveled, so as to form a passage-way to permit the grain to enter between the said operative faces. The stationary plate is at its ends formed with ears or walls g', adapted to come in comparatively close proximity to the reciprocating plate, and arranged to prevent the grain or the meal from escaping longitudinally from between the grinding-surfaces. The stationary bar E is upon its operative face and immediately below the beveled portion provided with recesses e' e', into which the grain passes immediately after leaving the passage-way formed by the beveled faces d' and g'. After the grain has reached these recesses it is (when the machine is in operation) immediately caught or engaged with by the reciprocating plate or bar, which operates to break, crack, or crush it into particles small enough to permit them to pass downwardly away from the plates. To permit the particles to immediately escape after being broken or cracked, I provide channels, grooves, or passage-ways e² e², each arranged between two of the upper initial receiving recesses or pockets, so that in whichever direction the reciprocating plate may be moving the particles will be imme-

diately delivered to the one or the other of the passage-ways, which extend to the bottom of the stationary plate or bar E. After the material has been operated upon by the breaking or cracking surfaces it escapes through the passage-way between the top pieces of the frame, and may be received into a hopper or any other suitable receptacle, from which it may be carried by spouts or elevators to any desired point in the mill.

My invention is more especially applicable to producing flour from grain by what is now in the art known as the system of "gradual reduction"—that is to say, I can employ a series of these machines having horizontally-arranged grinding-plates of substantially the character which I have described, and pass the product of one machine to the next in the series until it has been reduced to the required degree of fineness. In the machine which first receives the grain the plate or bar E is adjusted so as to merely crack the berries into large particles, preferably so as to break them into halves. After it is cracked the material can be carried to any suitable scalping or cleaning mechanism for removing the fuzz and dirt, which, as is well known, can be better removed after the grain has been thus treated. It is then returned to a reducing-machine similar to the one described, except that the stationary grinding-face D' is adjusted somewhat nearer to the reciprocating face. After it has been operated upon by this second machine it can be then carried to a cleaning device before subjecting it to further reducing operations, which latter can be carried on as long as it is necessary in substantially the way now followed in gradually reducing grain.

If desired, all the reducing-machines of the series may be arranged in a vertical line, and the material may be passed downward from one to the other after going through the appropriate cleaning mechanism at each stage. If preferred, the cleaning or scalping mechanism may be arranged in the same machine or in the same vertical series of machines.

A grinding or reducing mechanism of the kind I have described I have found to be much more desirable than rolls, disks, or stones, which have heretofore been used for gradual reduction. It is well known that the rolls and disks can be made only at considerable cost, and that the mechanism employed to operate them requires a large amount of power.

The expense of a machine of my improved character is about one-tenth that of a machine of the ordinary kind employing rolls, and the power required to operate mine is about one-fifth that of a roller-machine of the same capacity.

I do not wish to be limited to the specific form of supporting frame-work which I have shown, having this to illustrate in a simple manner a practical method of carrying out my

improvements. Nor do I wish to be limited to the exact form of mechanism which I have shown for imparting motion to the reciprocating surface, as it will be readily seen that these devices can be easily varied by one skilled in the art without changing the important parts of the invention. Nor do I wish to be limited to the exact shape of the recesses or pockets e' in the stationary grinding-surface, or to the exact shape of the escape-channels e², below and between the receiving ones.

J J are metal springs, attached to the bar G at the ends, and also to the frame-work, as shown at j j. These springs operate to insure that the reciprocating plate shall move smoothly and greatly reduce the power required to operate it. Preferably these springs are so arranged as to support the plate or bar G—that is, so that it shall be flexibly mounted.

I do not herein claim any of the features which I have shown and described, except the combinations specifically set forth in the following claims, reserving to myself the right to claim all other patentable matters in another application which I have filed as a division of this case.

What I claim is—

1. In a machine for reducing grain to flour, the combination, with the reciprocating grooved, recessed, corrugated, or ribbed plate, of an opposing plate having initial receptacles, pockets, or recesses, or recesses e', and passage-ways which permit the material to escape after it has been cracked, substantially as set forth.

2. In a machine for reducing grain to flour, the combination, with a reciprocating grinding or cracking plate, of an opposing plate having initial receptacles, pockets, or recesses, and escape passage-ways, each situated between two of said initial receptacles or recesses, substantially as set forth.

3. In a machine for reducing grain to flour, the combination of two opposing grinding-surfaces, of which one reciprocates relatively to the other, and of which one is provided with initial receptacles, pockets, or recesses for holding the berries while being cracked, and passage-ways which permit the cracked material to escape immediately after leaving said initial receptacles or recesses, substantially as set forth.

4. In a machine for reducing grain to flour, the combination, with a cracking or grinding plate, of an opposing reciprocating grinding or cracking plate, and springs arranged, substantially as set forth, to support or partially support flexibly said reciprocating bar or plate.

In testimony whereof I affix my signature in presence of two witnesses.

CHARLES S. RIDER.
